Primary Examiner — Marissa J Cash(74) *Attorney, Agent, or Firm* — Dorsey & Whitney LLP(57) **CLAIM**

The ornamental design for a drone, as shown and described.

DESCRIPTION

FIG. 1 is a top, front isometric view of a drone in accordance with an embodiment of the present design.

FIG. 2 is a rear elevation view of FIG. 1.

FIG. 3 is a front elevation view of FIG. 1.

FIG. 4 is a top plan view of FIG. 1.

FIG. 5 is a bottom plan view of FIG. 1.

FIG. 6 is a right side elevation view of FIG. 1, with the left side elevation view being a mirror image thereof; and, FIG. 7 is a top, rear isometric view of FIG. 1.

The broken lines illustrate portions of the drone that form no part of the claimed design.

1 Claim, 7 Drawing Sheets(56)
